UNITED STATES PATENT OFFICE

148,692

DESIGN FOR A COSMETIC DISPLAY BOX

Elizabeth N. Graham, New York, N. Y.

Application September 4, 1947, Serial No. 141,201

Term of patent 14 years

(Cl. D80—5)

To all whom it may concern:

Be it known that I, Elizabeth N. Graham, a citizen of the United States of America, residing in New York city, county of New York, and State of New York, have invented a new, original, and ornamental Design for a Cosmetic Display Box, of which the following is a specification, reference being had to the accompanying drawing, forming part thereof, wherein,

I claim:

The ornamental design for a cosmetic display box, substantially as shown.

ELIZABETH N. GRAHAM.
